CLAIM

The ornamental design for a hockey stick, as shown and described.

DESCRIPTION

FIG. 1. Is a top view of my hockey stick;

FIG. 2. Is a bottom view thereof;

FIG. 3. Is a right side elevational view thereof;

FIG. 4. Is a left side elevational view thereof;

FIG. 5. Is a front view thereof;

FIG. 6. Is a rear view thereof;

FIG. 7. Is a cross sectional view taken along the line 7—7 of FIG. 5;

FIG. 8. Is a rear view of an alternative embodiment of my hockey stick for opposite hand holding as opposed to that shown in FIG. 6; and,

FIG. 9. Is a cross section view taken along the line 9—9 of FIG. 8.

The broken line showing is for illustrative purposes only and forms no part of the claimed design.
